UNITED STATES PATENT OFFICE

2,638,171

AUTOMATIC VARIABLE PITCH PROPELLER

Freeman C. Foss, Twin Falls, Idaho

Application September 30, 1947, Serial No. 777,004

1 Claim. (Cl. 170—160.51)

1

This invention appertains to novel and useful improvements in propellers of the automatic controllable pitch type.

An object of this invention is to provide an improved blade construction which, by selectively shaping certain portions thereof, the blade is urged to selected controlled pitch positions while being acted on by a fluid medium.

Another object of this invention is to provide means for retaining propeller blades in the reversed flow position.

Another object of this invention is to provide means for adjustably controlling the travel of the blades.

A further object of this invention is to provide means for controlling the pitch of the propeller blades in order that the usual power plant associated therewith may be operated at the most efficient horsepower output.

Another purpose of this invention is to provide a relatively simple device capable of performing all of the above mentioned objects which is commercially feasible, practical and smoothly operative.

Other objects and features of novelty will become apparent to those skilled in the art, in following the description of the preferred embodiment of the present invention, illustrated in the accompanying drawings, wherein:

Figure 1 is an elevational view of the present invention;

Figure 2 is a fragmentary front view of the invention disclosed in Figure 1 and taken substantially on the line 2—2 thereof and in the direction of the arrows;

Figure 3 is a longitudinal sectional view of the actuating means with the propeller blades removed, taken substantially on the line 3—3 of Figure 2 and in the direction of the arrows;

Figure 4 is a side view of the invention disclosed in Figure 1, the blades being in a reversed position and portions being broken away in section to illustrate details of construction;

Figure 5 is a perspective view of the cam means forming part of the invention and the offset shaft for pivoting the blades;

Figure 6 is a reduced plan view of the body member forming part of the invention, portions being broken away to illustrate details of construction;

Figures 7, 8 and 9 are sectional views of the blade construction taken on the respective lines of Figure 1.

The device illustrated by the present invention may be utilized with substantially all outboard

and inboard motors as either an accessory or, if desired, a stock part. The general operation of the invention is relatively simple and will be set forth at this time, since this will lead to a better understanding of the mechanical elements to be set forth hereinafter.

A plurality of blades 10 are provided which, due to a particular flare back on the trailing edge, the pitch of the blades vary whenever the motor speed is changed. Each of the blades utilized in the present invention is pivoted at substantially the center of pressure or in a plane parallel or substantially parallel thereto. Of course, it is well known that the center of pressure varies under certain conditions. However, it is also realized that the said center of pressure varies only within certain limits and it is within these limits that the pivot for the blades is secured. Due to the water pressure increasing on the blades as the same increases in torque and decreasing when the motor is decelerated or torque is lessened, the blades always seek a predetermined value of pitch angle, commensurate with the most efficient operation of the associated power means.

There is provided cam means for actuating certain elements to be described later, and this cam means is provided with a flat part whereby the blades may even be held in a position to effect traction in a reverse direction. Under these conditions the pivot point of each blade is in a dead center relation with regard to an edge of the cam and the urging force of either the spring or the hydraulic means.

Taking, now, a feature of the present invention, the blades will be described in detail. The leading edge of each blade is provided with a slight sweep back 12. The trailing edge of each blade is provided with a forwardly flared portion 14. The last-mentioned flared portion forms a material part of the present invention, since it is this forwardly flared portion which, when utilized in conjunction with the pivot location, urges the blades automatically to the proper pitch position. A cam 16 is secured to the base of each blade and the cam has a flat part or seat 18.

A shaft 20 is secured to each cam 16 and is substantially at the center of pressure of the blade as a whole. It will be noted that the said shaft 20 is supplied with threads at the terminal portion thereof.

A body member or housing 22 is provided for use in conjunction with the present invention. For this construction, reference is made to Figure 3 wherein there is disclosed the body mem-

ber 22 having a sleeve 24 slidably disposed thereover. Bearings 26 with apertures 27 are secured to, or formed integral with the body member 22 adjacent one end thereof for the purpose of supporting the shaft 20 of the respective blades. The flat cams 16 engage a complementary cam surface 17 on the forward portion of the said sleeve 24 and, as the blades are rotated about the pivot pin 20, the sleeve 24 is urged axially of the housing or body member 22, against the biasing action of a spring 28.

The spring 28 is disposed between the sleeve 24 and the housing 22. The terminal portion of the said housing 22 is externally threaded and a nut 30 applied thereto in order to retain the said spring 28 within the sleeve 24. Suitable packing means 32, conventional in nature, may be supplied as well as any number of washers and the like, which may be found advantageous. It will be noted that a plurality of apertures 34 is provided in the body member 22 for the purpose of preventing vacuum lock between the member 22 and sleeve 24.

A power shaft 36 extends through the said housing 22 and a shear pin 38 extends therethrough and through said power shaft. The terminal portion of the shaft 36 is received in a second housing 40, positioned within a bore in the said housing 22. This second housing 40 is threaded received on the terminal portion of the said power shaft 36. A limiting bolt 42 is provided in the said second housing 40 and engages the said power shaft 36.

Means for limiting the pivotal travel of the blades is provided. This means consists of a pair of set screws 44 and 46, respectively, which are adjustably secured in holes in an outer flange 48 of said housing 22. These set screws engage a selected portion of the said cams 16, as is quite apparent from an inspection of Figure 1.

As is seen in Figure 1, the shaft 20 extends through the bore 27 of the bearing 26 and a suitable castle nut or the like 48 is applied to the threaded portion thereof. Of course, a cotter pin 50, or the like, may be utilized in conjunction therewith for the usual function of retaining the castle nut in the desired, tight position.

It is noted that most outboard motors or even inboard motors utilize the conventional gasoline or oil as fuel. Accordingly, in marine engines of this nature, fouling and insufficient operation may be effected if the engine is operated very slowly for a long time. With the use of the present invention, the engine may run or operate at a higher value of R. P. M. and yet supply the same horsepower output or value of torque. Obviously, this permits higher efficiency of engine operation.

A portion of this reserved, slower speed of engine operation can be used to reverse the direction of the water displacement by the blades. At different values of torque, the blades, due to the flare back of the trailing edge and due to the advantageous position of the pivot on, or substantially on the center of pressure, assume varied angles of pitch. At very slow speed, the pitch angle approaches a reverse direction and even upon slower speed, the blades actually do reverse flow of displacement. Since the flat part 18 of the cam 16 is then disposed on the cam surface

17, the blades will be retained in this reverse direction until a burst of speed pulls them out of this reverse direction. The cams 16 may be designed in such a way that slight increase in speed 5 may be effected without pulling the blades from their reverse position in order to obtain a backward motion of the entire boat on which the invention is applied. Of course, since the blades are in the very slightly reversing direction or flow-producing direction, starting of the engine 10 will be materially reduced in difficulty due to the almost absence of torque required to propel the blades in this position.

Having described the invention, what is claimed 15 as new is:

In a controllable pitch propeller, a body member of longitudinal form and having a longitudinal axis, a sleeve concentrically located on the exterior of a part of said body member and slid- 20 able axially of said body member, means operatively connected with said sleeve and said body member yieldingly restricting relative axial movement of said sleeve and said body member, a bearing at one end of said body member, said bearing having openings therein each of which has a longitudinal axis perpendicular to said body member axis, blades, pivot pins secured to the root ends of said blades and disposed in said 25 openings thereby rotatably mounting said blades about axes of rotation normal to said longitudinal axis of said body member, cams fixed to the root ends of said blades and each cam having a land, complementary cam means on said sleeve contacted by said cams so that when 30 said blades are rotated a predetermined amount to move the sleeve away from said one end of said body member, said lands rest upon said cam means to retain said blades rotated, adjustable means on said body member and in the path of 35 rotation of said cams for limiting the rotation of said blades as the sleeve is moved toward the said one end of said body member, and means 40 comprising curved trailing edges of each of said blades for rotatably urging said blades to varied positions of blade pitch angle.
